US00D778837S

(12) **United States Design Patent** (10) **Patent No.:** **US D778,837 S**
(45) **Date of Patent:** **** Feb. 14, 2017**

(54) **MAGNETIC COMPONENT**

(71) Applicant: **Sumida Corporation**, Chuo-ku, Tokyo (JP)

(72) Inventor: **Satoru Yamada**, Miyagi (JP)

(73) Assignee: **Sumida Corporation** (JP)

(**) Term: **15 Years**

(21) Appl. No.: **29/531,261**

(22) Filed: **Jun. 24, 2015**

(51) LOC (10) Cl. **13-02**

(52) U.S. Cl.

USPC **D13/117**

(58) **Field of Classification Search**

USPC ..... D13/117, 101, 118, 133, 179, 183, 199; 123/634; 250/231.12; 336/83, 90, 92, 96, 336/160, 178, 192, 198, 200; D15/5, 199 CPC H01F 5/02; H01F 5/04; H01F 27/022; H01F 27/29; H01F 27/292; H01F 27/325; H01F 27/2847; H01F 41/061; H01F 41/10; H01F 17/04; H01F 17/043; Y10T 29/4902; Y10T 29/49069; Y10T 29/49071; Y10T 29/49073

(57) **CLAIM**

The ornamental design for a magnetic component, as shown and described.

DESCRIPTION

FIG. 1 is a perspective view of a magnetic component embodying my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.
